BARREL WASHING MACHINE

Filed Dec. 17, 1921

2 Sheets-Sheet 2

Inventor:

John H. Miller,
By Dreyerforth, Lee, Chittenden & Miller,
Attoys.

UNITED STATES PATENT OFFICE.

JOHN H. MILLER, OF CHICAGO, ILLINOIS.

BARREL-WASHING MACHINE.

Application filed December 17, 1921. Serial No. 522,975.

To all whom it may concern:

Be it known that I, JOHN H. MILLER, a citizen of the United States, residing at 7147 Perry Avenue, Chicago, in the county 5 of Cook and State of Illinois, have invented a new and useful Improvement in Barrel-Washing Machines, of which the following is a specification.

This invention relates to barrel washing 10 machines and is fully described in the following specification and shown in the accompanying drawings, in which Figure 1 is a front elevation of the machine, Fig. 2 is a side elevation partly in section on the 15 line 2 of Fig. 1, and Figs. 3 and 4 are partial vertical sections taken on the line 3 of Fig. 2.

The machine comprises a frame 10, having a shaft 11 secured thereto at one side, journaled in suitable bearings 12 and having a sleeve 13 mounted upon the opposite side and in alignment with the shaft 11. This sleeve is journalled in suitable bearings 14 and has an axle 15, extending therethrough, 25 as shown in Fig. 4. This axle is secured at its outer end in a bracket 16, by means of a pin 17, and has a bevel gear 18 keyed upon its inner end.

This bevel gear meshes with the bevel gear 30 19, which is keyed upon one end of the shaft 20, which is journalled in bearings 21. The opposite end of this shaft has a pinion 22 keyed thereon, which meshes with a large gear 23, which is carried by a short shaft, 35 not shown, which is journalled in the bearing 24 and which is carried by the outer end of the frame 10.

The side of the gear 23 is preferably flat and carries a plurality of pins 25, between 40 which a barrel or drum A may be loosely inserted and held.

The plate 26, having pins 27 which are singularly disposed to pins 25, is carried by the opposite side of the frame 10 and in 45 alignment with the axis of the gear 23. The plate 26 is swivelled upon the inner end of the screw 28, which is threaded through the block 29 on the end of the frame 10 and has a hand wheel 30, whereby it may be 50 screwed down upon the drum A. A locking lever 31 is also provided on the screw 28, by which it may be locked in adjusted position. A pulley 32 is keyed to the shaft 11 and a pulley 33 to the sleeve 13. A belt, not 55 shown, passing over either of these and driven from a suitable source of power, will

drive the machine. The method of operation is as follows. The locking lever 31 is released and the screw 28 backed off by means of the hand wheel 30, so as to raise the plate 26. The drum is then inserted and the plate 26 conveyed down by means of the screw 28, until the drum is gripped between the large gear 23 and the plate 26. The locking lever 31 is then set down so as to lock the screw 28 in this position. The bung B of the drum A is removed and a piece of chain or the like is then inserted and a quantity of washing fluid is poured in. The bung B is then inserted and screwed 70 down tight.

The frame is then set in motion and the barrel will be given turning action due to its turning about the axis of the shaft 11 and the sleeve 13. In addition to this the drum will be given a motion of rotation about its own axis, due to the fact that the bevel gear 19 is moved about the stationary gear 18, thereby causing the pinion 22 on the shaft 20 to drive the large gear 23.

As a result of this double motion the drum will be turned so as to bring the chain therein into contact with the entire inner surface of the drum and a thorough cleaning of the drum results.

While I have shown and described certain embodiments of my invention, it is to be understood that it is capable of many modifications. Changes therefore in the construction and arrangement may be made without departing from the spirit and scope of the invention as disclosed in the appended claims, in which it is my intention to claim all novelty inherent in my invention as broadly as possible in view of the prior art.

What I claim as new and desire to secure by Letters Patent, is:

1. A barrel washing machine comprising a frame, aligned trunnions at the sides of said frame, means for releasably supporting a barrel in said frame with its axis at right angles to said trunnions, means for turning said frame about its trunnions and means operating through one of said trunnions for simultaneously rotating said barrel about its own axis.

2. A barrel washing machine comprising a frame, aligned trunnions at the sides of said frame, means for turning said frame about its trunnions, an axle extending through one of said trunnions, a gear rotatably mounted in said frame and forming

a support for one end of said barrel, and means operably connecting said axle and gear for rotating said barrel about its axis.

3. A barrel washing machine comprising
5 a frame, aligned trunnions at the sides of said frame, means for turning said frame about its trunnions, an axle extending through one of said trunnions, a gear rotatably mounted in said frame and forming a
10 support for one end of said barrel, means for holding the opposite end of the barrel, an adjustable support for the last mentioned means, and means operably connecting said axle and gear for rotating said
15 barrel about its axis.

4. A barrel washing machine comprising a frame, aligned trunnions at the sides of said frame, means for turning said frame about its trunnions, an axle extending through one of said trunnions, a gear rotatably mounted in said frame and forming a support for one end of said barrel, a flat member having extensions surrounding the opposite end of said barrel, means carried by said frame, and journaled in said flat 20 member for adjustably clamping said barrel, and means operably connecting said axle and gear for rotating said barrel about its axis. 25

JOHN H. MILLER.
